MOUTHPIECE

Urban L. Plain, Minneapolis, Minn.

Application December 10, 1941, Serial No. 422,335

1 Claim. (CL 18—55)

This invention relates to improvements in smoking pipes and the like articles such as cigar and cigarette holders, and has particular reference to improvements in a bit for the stems of such articles.

One object of the invention is to provide a mouthpiece for tobacco users which will fit the mouth more comfortably than the present holders of this type, and which will be a cause of little or no irritation to the teeth and gums of the tobacco user.

A further object is to provide a mouthpiece of proper dimensions which will fit well between the teeth in a minimum of space and will be firmly and comfortably held in the mouth of the user. In the improved form of bit or mouthpiece, there is provided a holder which conforms to the teeth and mouth of the individual user. This is achieved by making an impression of the teeth of the individual in a bit and setting the impression, all of the operation being accomplished at a minimum cost and in a relatively short time.

The above and other objects will appear more clearly from the following detailed description when taken in connection with the accompanying drawing which illustrates a preferred embodiment of the inventive idea.

In the drawing:

Figure 1 is a perspective view of the manner in which an impression is obtained in making the improved mouthpiece;

Figure 2 is a perspective view of one side of the relatively soft mouthpiece in which the impression has been made;

Figure 3 is a perspective view of the reverse side;

Figure 4 is a view of an oven used in setting the mouthpiece in the final form.

Figure 5 is a side view of a complete pipe finished with the improved mouthpiece; and

Figure 6 is a top plan view of a pipe with the improved mouthpiece attached.

The improved mouthpiece may be made as follows: Suitable plastic material that sets up in at least two stages, is cold or hot molded into the desired shape of the mouthpiece. The molded mouthpiece should have substantially the shape and size of the desired finished product. The molded mouthpiece is furnished to the usual retail outlets with the remainder of the pipe. The individual for whom the improved mouthpiece is intended will make an impression of his teeth in the molded mouthpiece. This impression should conform to that part of the mouth where the pipe

or other holder is usually held and in the most comfortable position. The impression having been taken in the molded mouthpiece, the mouthpiece is then placed in an oven or in some instances in a heated mold to confer infusibility or a high degree of hardness and heat resistance upon the finished mouthpiece.

There is illustrated herein one way of producing this impression in a durable form, but it will, of course, be understood that such a mouthpiece may be made in a variety of different ways well-known to those skilled in the plastic and molding arts.

By way of example, a mouthpiece is made from phenol-formaldehyde resins by cold molding with or without fillers. Of course, it is to be understood that the mouthpiece can be made by hot molding. By whatever method the mouthpiece is formed the initial set should leave the material in such condition that the impression can fairly easily be made by the individual for whom the improved mouthpiece is intended.

The end 11 of the molded mouthpiece 10 is placed between the lower teeth 13 and upper teeth 12 and the impression made therein.

As shown in Figures 2 and 3 the impressions 15 and 16 of the teeth are shown in the end 11 of the mouthpiece 10.

The mouthpiece 10 with the impression therein is placed in a mold or oven. The mold or oven should be so constructed as to be capable of being quickly brought up to the desired temperature. The oven 17 may be heated by gas, electricity or by any other suitable means. As shown in Figure 4, the oven is heated electrically. The temperature of the mold or the temperature of the oven should be such that the plastic material employed will quickly set up in the final form.

In Figures 5 and 6 are shown a pipe 21 with the improved mouthpiece 10 secured in place and showing the impression therein.

It is to be understood that I do not restrict myself to any particular method of forming the improved mouthpiece or to any particular plastic as such methods and materials and combinations thereof will readily occur to those skilled in the art. It is apparent that the primary object of the invention is an improved mouthpiece composed of plastic material or other material capable of being formed as a mouthpiece, then have the impression made therein, and finally setting the material whereby the impression becomes a permanent part of the mouthpiece. The mouthpieces may be used for other purposes other than tobacco uses. For example, such as mouthpieces

for musical instruments, etc. The essence of the invention is the formation of the mouthpiece, the making of the impression therein which fits exactly the gripping surfaces of the teeth of the individual user and then giving the mouthpiece the final set.

The preformed mouthpiece capable of receiving the dental configuration of an individual set of teeth, and thereafter being set in the final hardness is the new article of manufacture which will be sold to the retail outlets. The retail dealers will be furnished with the necessary mold if heat and pressure is required or an oven if only heat treating is required to give the final set to the mouthpiece after the impression has been made therein.

In some instances it may be advisable to have

a properly shaped rod or other metal piece inserted into the opening while the impression is being made. In place of the metal rod a small tube liner may be inserted into the mouthpiece during the impression taking.

What I claim is:

A process of producing an improved mouthpiece for smoker's use by forming a mouthpiece from initially fusible plastic material capable 10 after being formed of receiving an impression in the outer surface thereof, making an impression in the formed mouthpiece with the teeth of the individual user, and then heat hardening the mouthpiece whereby a durable infusible plastic 15 mouthpiece is obtained.

URBAN L. PLAIN.
